UNITED STATES PATENT OFFICE.

GEORGE W. DYARMAN, OF NEW YORK, N. Y., ASSIGNOR TO NATHAN M. ROSEN, OF NEW YORK, N. Y.

HAT-FRAME.

1,184,729.

Specification of Letters Patent. Patented May 30, 1916.

Application filed August 25, 1915. Serial No. 47,234.

To all whom it may concern:

Be it known that I, GEORGE W. DYARMAN, a citizen of the United States, residing at New York, in the county and State of New York, have invented certain new and useful Improvements in Hat-Frames, of which the following is a full, clear, and exact description.

This invention relates to frames or bodies for women's hats, and its chief object is to provide an improved edge for the brim, whereby the brim can be covered and finished in less time and with less work than is the case with the ordinary hat frame.

15 A further object is to provide an edge construction which will give a neat and attractive finish and permit a variety of stitches to be employed in finishing the edge.

Another object is to provide an edge construction by which the brim may have a pliant edge and yet the brim itself be so reinforced or stiffened with a wire or other means as to retain its shape.

Still another object is to provide an edge construction in which the edge can be finished with a cord effect without the necessity of the milliner or trimmer actually inserting a cord in the brim.

To these and other ends the invention consists in the novel features hereinafter described.

The preferred form of the invention is illustrated in the accompanying drawing, in which—

35 Figure 1 is a sectional view, somewhat diagrammatic in character, of a hat frame provided with my improved edge construction. Fig. 2 is a detail perspective view of the edge construction shown in Fig. 1. Fig. 40 3 is a detail sectional view of the same, on a larger scale, showing the brim covered on both sides with plush or other pile-fabric and with the edge finished by "blind" stitching. Fig. 4 is a view similar to Fig. 3, but 45 with the edge finished by machine sewing. Fig. 5 is a detail sectional view showing a modification.

Referring to the drawing, 10 designates the crown of the hat frame and 11 the brim, 50 both being made of any suitable material, as for example, large-mesh fabric heavily sized or starched to give it the requisite stiffness. At top and bottom the crown is en-

circled by stiffening wires 12, in casings 13 made of bias strips of fabric stitched or otherwise secured to the hat body. A slight distance from the outer edge of the brim 11, say about five-eighths or three quarters of an inch from the edge, is a stiffening wire 14, secured to the brim in any convenient manner, as by stitches 15; and below and covering this wire is a fly 16, composed of a bias strip of material, preferably a large-mesh fabric suitably stiffened, which encircles the brim and has its outer edge flush with the brim-edge. This bias strip is sewed or otherwise fastened to the brim, preferably at its inner edge just behind or inside the wire 14, as by the stitching indicated at 17. 70

It will now be seen that in my improved edge construction the edge of the brim is double, forming, in the embodiment illustrated, an outwardly open "gutter", so to speak. When the brim is covered by the 75 milliner or finisher, the outer edges of the covering fabrics are simply turned over the two edges of the brim and tucked into the gutter, the work being done with the greatest ease and rapidity since the edges serve 80 most effectively to determine the lines of fold, making the two finished edges perfectly uniform throughout. As the turning-in of the fabrics progresses, the folds are secured in place. This can, of course, be 85 done by glueing, but stitching is in general preferable. In the latter case a variety of "finishes" can be used. For instance, the two fabrics can be "blind-stitched" to the frame inside their edges, as in Fig. 1, thereby giving a double edge effect; or they may be blind-stitched together as in Fig. 3, giving a thin edge; or they can be sewed together on a machine, giving the effect indicated in Fig. 4, in which the stitching is 90 represented at 18. 95

In the modified form of the invention, shown in Fig. 5, the stiffening wire, 19, is at the edge of the brim and the bias strip or fly 16 has its outer edge just inside the 100 wire, so that when the brim is covered and the edges of the fabrics secured inside the gutter the wire gives a "corded" effect to the edge of the brim.

It is to be understood that the invention 105 is not limited to the arrangements herein

specifically illustrated and described, but can be embodied in other forms without departure from its spirit.

I claim:

1. In a hat frame, a brim having a double edge forming an open gutter, in combination with upper and lower brim-covering fabrics having their outer edges turned into and fastened in said gutter, as set forth.
- 10 2. In a hat frame, a brim having a double edge forming an open gutter to receive the edges of brim-covering fabrics, and a stiffening wire secured to the brim and following the gutter inside the same at the bottom thereof, in combination with upper and lower brim covering fabrics having their outer edges turned into and fastened in said gutter.
- 15 3. In a hat frame, a brim, and a strip of fabric following the contour of the brim at the edge thereof and secured to the brim

at the inner edge of the strip, to provide an outwardly open gutter at the edge of the brim, in combination with upper and lower brim-covering fabrics having their outer edges turned into and fastened in said 25 gutter.

4. In a hat frame, a brim, a stiffening wire encircling the brim inside of the edge thereof, and a bias strip of fabric covering the wire and secured to the brim inside the 30 wire, to provide an outwardly open gutter, in combination with upper and lower brim-covering fabrics having their outer edges turned into and fastened in said gutter.

In testimony whereof I affix my signature 35 in the presence of two subscribing witnesses.

GEORGE W. DYARMAN.
